US0D1010053S

(12) **United States Design Patent** (10) Patent No.: **US D1,010,053 S**
(45) Date of Patent: ** Jan. 2, 2024

(54) **FRONT LATERAL CROSS MEMBER OF A TRIGGER BOW**

(71) Applicant: **Sean Hynds**, Uvalde, TX (US)

(72) Inventor: **Sean Hynds**, Uvalde, TX (US)

(**) Term: **15 Years**

(21) Appl. No.: **29/719,752**

(22) Filed: **Jan. 7, 2020**

(57) **CLAIM**

The ornamental design for a front lateral cross member of a trigger bow, as shown and described.

DESCRIPTION

FIG. 1 is a top perspective view of the front lateral cross member of a trigger bow showing a first embodiment of my new design.

FIG. 2 a bottom perspective view showing the first embodiment of my new design.

FIG. 3 is a top plan view showing the first embodiment of my new design.

FIG. 4 is a bottom plan view showing the first embodiment of my new design.

FIG. 5 is a left side elevation view of the first embodiment of my new design.

FIG. 6 is a right side elevation view of the first embodiment of my new design.

FIG. 7 is a front elevation view of the first embodiment of my new design.

FIG. 8 is a rear elevation view of the first embodiment of my new design.

FIG. 9 is a top perspective view of the front lateral cross member of a trigger bow showing a second embodiment of my new design.

FIG. 10 a bottom perspective view showing the second embodiment of my new design.

FIG. 11 is a top plan view showing the second embodiment of my new design.

FIG. 12 is a bottom plan view showing the second embodiment of my new design.

FIG. 13 is a left side elevation view of the second embodiment of my new design.

FIG. 14 is a right side elevation view of the second embodiment of my new design.

FIG. 15 is a front elevation view of the second embodiment of my new design.

FIG. 16 is a rear elevation view of the second embodiment of my new design.

FIG. 17 is a top perspective view of the front lateral cross member of a trigger bow showing a third embodiment of my new design.

FIG. 18 a bottom perspective view showing the third embodiment of my new design.

FIG. 19 is a top plan view showing the third embodiment of my new design.

FIG. 20 is a bottom plan view showing the third embodiment of my new design.

FIG. 21 is a left side elevation view of the third embodiment of my new design.

FIG. 22 is a right side elevation view of the third embodiment of my new design.

FIG. 23 is a front elevation view of the third embodiment of my new design.

FIG. 24 is a rear elevation view of the third embodiment of my new design.

FIG. 25 is a top perspective view of the front lateral cross member of a trigger bow showing a fourth embodiment of my new design.

FIG. 26 a bottom perspective view showing the fourth embodiment of my new design.

FIG. 27 is a top plan view showing the fourth embodiment of my new design.

FIG. 28 is a bottom plan view showing the fourth embodiment of my new design.

FIG. 29 is a left side elevation view of the fourth embodiment of my new design.

FIG. 30 is a right side elevation view of the fourth embodiment of my new design.

FIG. 31 is a front elevation view of the fourth embodiment of my new design; and,

FIG. 32 is a rear elevation view of the fourth embodiment of my new design.

The broken lines showing the side cross members of the trigger bow, the rear lateral cross member of the trigger bow, and the trigger in FIGS. 1-32 are illustrative of environmental structure only and form no part of the claimed design.
